ABSTRACT OF THE DISCLOSURE

A horizontally disposed heated sleeve, from which charges of molten metal are supplied by a reciprocating plunger to a gate and die cavity through a heated nipple which is aligned with the gate and open from the top of the sleeve, is connected by a supply conduit to a source of supply and is automatically refilled by maintaining the liquid level within the source of supply between the top of the charging sleeve and the top of the nipple.

This invention relates to die casting of metals and particularly to a system for automatically supplying molten metal from a heated "launder," or supply conduit, to one or more die casting machines, preferably to a battery of casting machines, of the kind in which a piston is reciprocated within a charging sleeve, to force a charge into a die cavity.

An object of the invention is to automatically refill the charging sleeve with molten metal, without any manual operation, as soon as it is emptied, or partly emptied, by the charging stroke of the piston and the piston has been retracted.

Another object of the invention is to reduce to a minimum the amount of slag by eliminating any runner and feeding as directly as possible from the charging sleeve to the gate of the die cavity and thus reducing the volume of molten metal required for each charge and reducing the size of charging sleeve that is required.

Another object of the invention is to save the time heretofore required in ladling molten metal into a charging sleeve or any other manual operation heretofore employed to actuate a lever or turn a valve for causing molten metal to be supplied into a charging sleeve.

Another object of the invention is to eliminate the enlarged portions of a launder or molten metal supply conduit heretofore employed to house goosenecks conventionally used as the charging sleeves in the casting of zinc and thus conserve floor space.

Another object of the invention is to increase the efficiency of die casting by saving space and the operator's time, and by decreasing waste, and increasing the number of castings produced per unit of time.

The invention will best be understood by reading the following description in connection with the drawings, in which:

FIGURE 1 is a top plan view of a system embodying the invention,

FIGURE 2 is an end cross sectional view taken on the lines 2—2 of FIGURE 1, and

FIGURE 3 is a side elevation partly in cross section taken on the lines 3—3 of FIGURE 1.

As shown herein the molten metal to be cast is supplied automatically, by gravity, from within a range of levels in a launder, to a heated charging sleeve which has an outlet port leading from the top or highest part of the sleeve to a gate defined between opposed die plates. It will be noted that the launder is of a uniform diameter and is not widened at intervals to provide a succession of spaces each adapted to receive a gooseneck charging sleeve, such for example as is shown in U.S. Patent

2

2,799,066. Where a number of die casting machines are being supplied from a common launder the provision of enlarged areas to receive gooseneck charging sleeves substantially decreases the floor space and thus decreases the number of diecasting machines which can be employed within a given area.

In FIGURE 1 a launder 10 of uniform diameter is shown which is supplied with molten metal from a furnace not shown. From the launder 10 branch conduits 12 and 14 lead to the inlet ports 16 and 18 respectively of the charging sleeves 20 and 22 of a plurality of die casting machines, which may be conventional apart from the parts illustrated herein. Since the means for reciprocating the pistons 24 and 26 within sleeves 20 and 22 respectively may be conventional it is not necessary to show or describe it herein. The inlet ports 16 and 18 are located in advance of the position of pistons 24 and 26 respectively when fully retracted.

As shown herein the charging sleeves 20 and 22 are disposed horizontally, the forward ends of the sleeves are closed, and the outlet ports are in the form of short nipples 28 and 30 which are respectively aligned with the planes of the parting line between the sets of die plates 32, 34 and 36, 38 and communicate respectively with the gates 40 and 42, defined between the opposed faces of the pairs of die plates, which in turn communicate with the die cavities 44 and 46 which are also defined between the faces of the opposed pairs of die plates. The sleeves 20 and 22 and their discharge port nipples 28 and 30 respectively are heated, as by the electric heating coils c.

It will be noted that the level of the molten metal m within the launder 10 is preferably above the top of the sleeves 20 and 22, and so the sleeves will be completely refilled with molten metal, automatically, by gravity, immediately after each reciprocation of the charging pistons, and that the level of the molten metal m within the launder is below the top of the discharge port nipples 28 and 30 and that therefore the sleeves cannot overflow, with spillage from the nipples, as for example when the pairs of die plates are separated and the communication of the nipples with the gates 40 and 42 is thus broken.

With the structure described above no manual operation is required in connection with filling the charging sleeves and the resulting saving of time makes possible an increase in production of castings since the time required per casting cycle is accordingly reduced.

While the invention is not limited to the casting of any particular metal nor primarily concerned with the material used for the casting sleeve, if sleeves made of steel are employed the invention is particularly useful for casting zinc and other metals having a melting point below the temperature continual exposure to which is damaging to steel. Obviously aluminum and other metals having a higher melting point may be automatically charged into, and allowed to stand in, sleeves made of material impervious to the higher temperatures.

There has thus been provided apparatus and method by the use of which the above stated objects are realized in a thoroughly practical way.

What I claim is:

1. The method of casting metals in a die cavity defined between opposed die plates and having a gate also defined between said die plates, which comprises, supplying molten metal to said gate from a heated outlet nipple located on the top of a heated charging sleeve having reciprocable means therein for forcing molten metal from within the sleeve through said gate into said die cavity, and automatically refilling the sleeve when the reciprocable means is retracted from a supply of molten metal the level of which is below the top of said nipple and above the top of the interior of said charging sleeve.

2. The method of casting metals which comprises, providing a die cavity defined between opposed die plates and having a gate also defined between said die plates, providing a charging sleeve with an outlet nipple disposed directly below said gate in alignment with said gate, and with reciprocable means therein for forcing molten metal from within the sleeve through said gate into said die cavity, maintaining the liquid level within the launder conduit between the level of the interior of the sleeve at the top and the level of the discharge end of the nipple, and automatically refilling the sleeve when the reciprocable means is retracted, from a supply of molten metal the level of which is below the top of said nipple and above the top of the interior of said charging sleeve.
